FINISHING SEAM AND METHOD

Walter Myers, Bridgeport, Conn., assignor to The
Singer Manufacturing Company, Elizabeth,
N. J., a corporation of New Jersey

Application March 17, 1938, Serial No. 196,324

16 Claims. (Cl. 112—262)

This invention relates to improvements in the methods of joining fabric-sections and in articles of manufacture having fabric-sections joined by stitched seams.

In the manufacture of high-grade wearing apparel and other articles, in which the proximate margins of fabric-sections are united by stitched seams, difficulty has been experienced heretofore in forming narrow joining seams of finished appearance when said fabric-sections have cross-seams.

The present invention has for its object to provide a simple method of securely joining the proximate margins of fabric-sections, whereby the joining seam has the requisite uniformity of appearance throughout the length thereof, and whereby the raw edges of the joined margins are effectively concealed.

The invention will be understood from the following description, in connection with the accompanying drawing which illustrates the improved method of joining fabric-sections and in which:

Fig. 1 represents, in perspective, two fabric-sections having their overlapping margins initially united by a row of straightaway stitches. Fig. 2 illustrates, in perspective and partly in section, a finished seam formed by folding and zigzag stitching the initially united fabric-sections of Fig. 1. Fig. 3 represents, in perspective, two fabric-sections having abutted edges initially united by a row of zigzag stitches. Fig. 4 illustrates, in perspective and partly in section, a finished seam formed by folding and zigzag stitching the initially united fabric-sections of Fig. 3. Fig. 5 represents, in perspective, two fabric-sections having overlapping margins initially joined by a row of zigzag stitches. Fig. 6 illustrates, in perspective and partly in section, the finished seam formed by folding and stitching the initially united fabric-sections of Fig. 5. Fig. 7 illustrates, in perspective and partly in section, a finished seam corresponding to Fig. 4 but with the fold secured by two rows of straightaway stitches.

Referring to Fig. 1 of the drawing, fabric-sections 1 and 2 having proximate margins thereof disposed in overlapping relation are initially united by a row of straightaway stitches 3, with the bodies of said fabric-sections extending in opposite directions away from the united margins thereof. The uniting of the overlapping margins of the fabric-sections 1 and 2, as described, constitutes an initial step in the joining of said fabric-sections, and the uniting stitches,

made by hand or by machine, may be of any suitable or preferred form.

An S-shaped fold is then formed in the initially united fabric-sections in a zone thereof to dispose the united margins between the outer plies of the fold. In a preferred manner of forming this S-shaped fold, the initially united margins are together inverted to overlie the fabric-section 2 by folding said fabric-section 2 on a line B—B at one side of and substantially parallel to the row of stitches 3. Also, the fabric-section 1 is folded on a line A—A at the opposite side of and substantially parallel to the row of stitches 3 to overlie said inverted margins. By thus folding the fabric-sections, the portions thereof between the lines A—A and B—B; i. e., the united margins of said fabric-sections, are inverted between the fabric-sections to constitute the middle portion of the S-shaped fold illustrated in Fig. 2 of the drawing.

This method of folding the fabric-sections has the advantage that the body portions of said fabric-sections remain right side up, the united margins only thereof being inverted. Furthermore, the preferred manner of folding the fabric-sections may be conveniently effected by employing a sewing machine provided with a well-known separable pleat-folder, one form of which is disclosed, for example, in the U. S. patent to W. Gibson, No. 930,469, Aug. 10, 1909. A separable pleat-folder of this type not only facilitates handling of the work, but it also provides the requisite clearance for cross-seams while maintaining the desired fold-lines.

However, a similar effect may be obtained by under folding the fabric section 1 on substantially the line A—A, Fig. 1, at one side of the row of stitches 3, whereby said fabric-section underlies the united margin of the other fabric-section 2, and by folding the fabric-section 2 on a line B—B, at the opposite side of the row of stitches 3, to overlie the margin of the fabric-section 1. When thus folded, the body portions of the fabric-sections are inverted to contactually overlie and underlie the united margins thereof.

The plies of the described S-shaped fold are then secured together by a row or rows of stitches. The fold-plies may be secured together by a row of stitches which, as illustrated in Fig. 2 of the drawing, may be a row of zigzag stitches 4 which are preferably disposed within the fold edges and penetrate the several plies of the fold. Obviously, the fold plies may be secured together by one or more rows of straightaway stitches, or

by any suitable ornamental covering-seam, as may be preferred.

- Instead of initially joining overlapping margins of the fabric-sections, as in Fig. 1, the edges of the fabric-sections may be initially disposed in abutting relationship. As illustrated in Fig. 3 of the drawing, the abutting edges of fabric-sections 5 and 6 are united by a row of zigzag stitches 7 anchored in the fabric-section margins 8 at opposite sides of said abutting edges. By now folding the united fabric-sections, on the lines A—A and B—B, so that the fabric-section 5 contactually overlies its margin and the margin of the fabric-section 6, and so that the fabric-section 6 contactually underlies its own margin and the margin of the fabric-section 5, a three-ply S-shaped fold will be formed as illustrated in Fig. 4 of the drawing. It will be noted that the uniting stitches 7 are disposed in the middle ply of the S-shaped fold of Fig. 4 and that said stitches 7 are effectively concealed by the outer plies of the fold. The three plies of the S-shaped fold of Fig. 4 are then secured together by a row of zigzag stitches 8, or they may be secured together by two rows of straight-away stitches 9, Fig. 7, or otherwise as may be preferred.

In Fig. 5 of the drawing, the proximate margins of two fabric-sections 10 and 11 are disposed in overlapping relation and the overlapping margins are initially united by a row of zigzag stitches 12, instead of by a straightaway row of stitches, as illustrated in Fig. 1. The fabric-sections 10 and 11 are then folded on the lines A—A and B—B, in the same manner as in Fig. 2, the fold plies being secured together by a row of straight-away stitches 13.

It will therefore be understood that the present invention, in its broader aspects, is not limited to any specific means for initially uniting the fabric-sections, nor is it limited to any specific stitch-formation for securing together the fold plies. The primary purpose of initially uniting the fabric-sections is to facilitate the folding of the sections as herein described, whereby the united edges of the fabrics and the initial uniting means are effectually concealed.

Having thus set forth the nature of the invention, what I claim herein is:

50. 1. The method of forming a finishing seam in fabric-sections having proximate margins thereof united by stitches, comprising, folding one of said fabric-sections on a line at one side of said row of stitches to overlie the united margins, folding the other fabric-section on a line at the other side of said row of stitches to underlie the united margins, and securing the fold-plies together by stitches.
55. 2. The method of forming a finishing seam, comprising uniting proximate margins of fabric-sections by a row of stitches, folding one of said fabric-sections on a line at one side of said row of stitches to overlie the united margins, folding the other fabric-section on a line at the other side of said row of stitches to underlie the united margins, and securing the fold-plies together by stitches.
60. 3. The method of forming a finishing seam in fabric-sections extending in opposite directions away from united margins of said fabric-sections, comprising folding said fabric-sections on lines adjacent and substantially parallel to the united margins thereof to respectively overlie and underlie said united margins, and securing together the fold-plies by stitches.

4. The method of forming a finishing seam in fabric-sections extending in opposite directions away from united margins of said fabric-sections, comprising inverting the united margins upon one of the fabric-sections by folding said fabric-section on a line at one side of and substantially parallel to the margin-uniting means, folding the other fabric-section upon the inverted margins on a line at the opposite side of and substantially parallel to the margin-uniting means, and securing together the fold-plies by stitches.

5. The method of forming a finishing seam, comprising initially uniting the proximate margins of fabric-sections extending in opposite directions away from said proximate margins, forming an S-shaped fold in said fabric-sections in a zone thereof to dispose the united margins between the outer plies of said fold, and securing together the plies of said fold by stitches.

6. The method of forming a finishing seam, comprising initially uniting by stitches the proximate margins of fabric-sections extending in opposite directions away from said proximate margins, forming an S-shaped fold in said fabric-sections in a zone thereof to dispose the united margins between the outer plies of said fold, and securing together the plies of said fold by stitches.

7. The method of forming a finishing seam, comprising initially uniting the proximate margins of fabric-sections extending in opposite directions away from said proximate margins, forming an S-shaped fold in said fabric-sections in a zone thereof to dispose the united margins between the outer plies of said fold, and securing together the plies of said fold by zigzag stitches.

8. The method of forming a finishing seam, comprising initially uniting the proximate margins of fabric-sections extending in opposite directions away from said proximate margins, forming an S-shaped fold in said fabric-sections in a zone thereof to dispose the united margins between the outer plies of said fold, and securing together the plies of said fold by substantially parallel rows of straightaway stitches.

9. The method of forming a finishing seam, comprising initially uniting by stitches the proximate margins of fabric-sections extending in opposite directions away from said proximate margins, forming an S-shaped fold in said fabric-sections in a zone thereof to dispose the united margins between the outer plies of the fold, and securing together the plies of said fold by zigzag stitches.

10. The method of forming a finishing seam, comprising initially uniting by stitches the proximate margins of fabric-sections extending in opposite directions away from said proximate margins, forming an S-shaped fold in said fabric-sections in a zone thereof to dispose the united margins between the outer plies of the fold, and securing together the plies of said fold by zigzag stitches disposed within the fold edges.

11. The method of forming a finishing seam, comprising initially uniting by zigzag stitches the abutting margins of fabric-sections, forming an S-shaped fold in said fabric-sections in a zone thereof to dispose said zigzag stitches between the outer fold-plies, and securing together the plies of said fold by stitches.

12. The method of forming a finishing seam, comprising initially uniting by zigzag stitches the proximate margins of fabric-sections, forming an S-shaped fold in said fabric-sections in a zone thereof to dispose said zigzag stitches between

2,169,590

the outer fold-plies, and securing together the plies of said fold by zigzag stitches.

13. The method of forming a finishing seam, comprising initially uniting by stitches the overlapping margins of fabric-sections extending in opposite directions away from said proximate margins, forming an S-shaped fold in said fabric-sections in a zone thereof to dispose said stitches between the outer fold-plies, and securing together the plies of said fold by stitches.

14. The method of forming a finishing seam, comprising initially uniting by stitches the overlapping margins of fabric-sections extending in opposite directions away from said proximate margins, forming an S-shaped fold in said fabric-sections in a zone thereof to dispose said stitches between the outer fold-plies, and securing said fold by zigzag stitches.

15. The method of forming a finishing seam, comprising initially uniting by zigzag stitches the overlapping margins of fabric-sections extending in opposite directions away from said margins, forming an S-shaped fold in said fabric-sections in a zone thereof to dispose said zigzag stitches between the outer fold-plies, and securing together the plies of said fold by zigzag stitches.

16. An article of manufacture having the proximate margins of two fabric-sections united by a row of stitches disposed in the middle ply and concealed by the outer plies of an S-shaped fold formed in said fabric-sections, said S-shaped fold having the plies thereof secured together by stitches.

WALTER MYERS.
